UNITED STATES PATENT OFFICE

GEORGE A. GILLEN, OF BRONX, NEW YORK

DESIGN FOR A COMBINED SWITCH CASING AND MOUNTING BRACKET OR SIMILAR ARTICLE

Application filed November 3, 1932. Serial No. 45,720. Term of patent 14 years.

To all whom it may concern:

Be it known that I, GEORGE A. GILLEN, a citizen of the United States, residing at Bronx, county of Bronx and State of New York, have invented a new, original, and ornamental Design for a Combined Switch Casing and Mounting Bracket or Similar Article, of which the following is a specification, reference being had to the accompanying drawing, forming part thereof.

Fig. 1 is a top perspective view of the device.

Fig. 2 is a bottom plan view of the device.

I claim:

The ornamental design for a combined switch casing and mounting bracket or similar article, substantially as shown.

GEORGE A. GILLEN.
